(57) **CLAIM**

We claim the ornamental design for a material trimmer for cutting paper and the like, as shown and described.

DESCRIPTION

FIG. 1 is an isometric view of a material trimmer for cutting paper and the like showing our claimed design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The ornamental design which is claimed is shown in solid lines in the drawings. The broken line showing is directed to environment and is for illustrative purposes only; the broken lines form no part of the claimed design.
